CLAIM

The ornamental design for a structured-core laminate panel, as shown and described.

DESCRIPTION

FIG. 1 is top right perspective view of a structured core laminate panel incorporating our design;

FIG. 2 is a front, facing view thereof;

FIG. 3 is a right side view thereof;

FIG. 4 is a top plan view thereof;

FIG. 5 is a rear view thereof;

FIG. 6 is a left side view thereof; and,

FIG. 7 is a bottom plan view thereof.

The broken lines are included for the purpose of showing environmental portions of the structured-core laminate panel and form no part of the claimed design.
